UNITED STATES PATENT OFFICE.

FRANK L. WRIGHT, OF CHICAGO, ILLINOIS, ASSIGNOR TO THE LUXFER
PRISM PATENTS COMPANY, OF SAME PLACE.

DESIGN FOR A PRISM-LIGHT.

SPECIFICATION forming part of Design No. 27,982, dated December 7, 1897.

Application filed October 20, 1897. Serial No. 655,850. Term of patent 14 years.

To all whom it may concern:

Be it known that I, FRANK L. WRIGHT, a citizen of the United States, residing at Chicago, in the county of Cook and State of Illinois, have invented a certain new and useful Design for Prism-Lights, of which the following is a description.

My invention relates to a new and original design for prism-lights and is illustrated in the accompanying drawings, wherein—

Figure 1 is a view of the back of a prism-light embodying my design. Fig. 2 is a section through Fig. 1 on line 2 2.

I have illustrated in the drawings a prism-light A, provided on one side with a series of projecting ribs or prisms B, the other side of the light being provided with a pattern or or-

namental figure, as shown at C, the figure being surrounded by a plain border D.

The essential feature of my design is a prism-light provided on one side with prisms and on the other side with a pattern or ornamental figure surrounded by a plain border.

I claim—

A design for a prism-light substantially as shown and described, comprising a body portion provided on one side with a series of projecting ribs or prisms and on the other side with an ornamental design or figure surrounded by a plain border.

FRANK L. WRIGHT.
